(57) **CLAIM**

The ornamental design for a guarding apparatus for dental treatment, as shown and described.

DESCRIPTION

FIG. 1 is a perspective view of a guarding apparatus for dental treatment;

FIG. 2 is a front view of the design;

FIG. 3 is a rear view of the design;

FIG. 4 is a left-side view of the design;

FIG. 5 is a right-side view of the design;

FIG. 6 is a top plan view of the design; and,

FIG. 7 is a bottom plan view of the design.
